her Attorney

UNITED STATES PATENT OFFICE.

JOSEPHINE M. LEAHY, OF HOUSTON, TEXAS.

FILING SYSTEM.

Application filed August 24, 1921. Serial No. 495,045.

To all whom it may concern:

Be it known that I, JOSEPHINE M. LEAHY, a citizen of the United States, residing at Houston, in the county of Harris and State 5 of Texas, have invented certain new and useful Improvements in Filing Systems, of which the following is a specification.

This invention relates to recording means, or to filing systems for use in general and 10 surgical pathological research work, or in hospitals, whereby the processes which may occur in diseased states of the several organs of the body may be positively traced, their peculiar phases observed and compared, and 15 phenomena noted, the efficiency of the system increasing in accordance to the degree to which it is extended.

A novel feature of the invention, resides 20 in the provision of packs of index cards or guides, each constituting collectively a unit, intended to contain the records of diseases included in one section of a sectionalized classification list of diseases, arranged according to current nomenclature, each section 25 being devoted to diseases which attack a particular part of the body, each unit being divided into groups or divisions, and each division having a definite identifying color, to thereby convey to one familiar 30 with the system, that information of a certain character will always be found under that color, and all the colors in all units being always arranged in the same relative order.

35 A further object of the invention is the provision of means in each unit of the system, whereby to simultaneously locate, by means of a black line carried by a mortality card, the border of each division and the 40 total resulting deaths caused by the disease recorded therein, so that one familiar with the signification of the color of that particular division (which for example may designate "Complication" under "Section 45 24," entitled "Intestines" of the classified list mentioned in the foregoing) may readily ascertain, without handling all the complication cards, the number of deaths due to complications.

50 Another object of the invention is to provide, in a system of the class described, supplemental white index cards for each division, adapted to be inserted as occasion requires, each white card bearing an identification mark of the same color as that of

the division into which it is intended to be inserted, so that the cards may be withdrawn and indiscriminately mixed, and still be easily replaced in their respective divisions.

60 A still further object of the invention is to provide a filing system of the class described, whereby not only the number alone of similar diseases and their behavior may be recorded for comparison, from widely 65 separated institutions, but whereby special conditions and unexpected results may be recorded to note their average frequency, and association of one condition with another.

70 Other objects and advantages of the invention will be pointed out throughout the specification, the preferred form of the invention being shown in the accompanying drawings of which:

75 Figure 1 is a perspective view of a pack of index cards, embodying the invention, two section leader cards being shown, the cards between same representing a complete section, the divisions thereof being 80 indicated by the heavy transverse lines.

Figure 2 is a diagrammatic view, showing the upper long edge of the cards and the inscribed titles thereon, the cards collectively constituting a complete section 85 covering diseases of the intestines.

Figure 3 is a diagrammatic view, cross-hatched to indicate the several division colors, thereby illustrating how the divisions are distinctly discernible, and how 90 clearly the mortality cards define the borders thereof.

Figure 4 is a front view of one of the supplementary cards, and Figure 5 is a diagrammatic view of a part of the classification index cards.

95 As stated in the foregoing, this system has been invented to supply much-needed information for scientific research, it having been found that count alone is of little 100 use, in the absence of opportunity to compare and note the resultant differentiation between a large number of similar diseases under identical and varying conditions. It is a matter of great difficulty to ascertain 105 how many cases of a certain disease had been treated, say, for a period of months, in even well-known hospitals, how many of these acted as a complication, how many cases primary of the disease developed.

oped complication, and under what circumstances and conditions. To collect reliable information along these lines, applicant has found that even in the better regulated hospitals the individual charts of the thousands of patients being treated in these institutions are solely relied upon to glean any detail knowledge in the interest of health preservation or restoration.

10 According to the nomenclature of one hospital diseases have been classified, one classification having forty-one sections, beginning with:

Section 1. General diseases:

- 15 A—Infective.
- B—Syphilis.
- C—Gonorrhœa.
- D—Tuberculosis.
- E—General injuries.

20 Section 2. Diseases due to animal parasites.

Section 3. Diseases due to metabolism.

Section 4. Diseases peculiar to infancy.

Section 5. Diseases due to physical agents.

25 Section 6. Diseases due to poisonings and intoxications.

Section 7. Tumors:

- A—Malignant.
- B—Benign.
- C—Mixed.

30 Section 24. Intestines:

- A—Appendicitis.
- B—Appendicitis, acute.
- C—Appendicitis, acute, with abscess.
- D—Appendicitis, acute, with perforation.
- E—Appendicitis, acute, with peritonitis.
- F—Appendicitis, catarrhal.

40 G—Appendicitis, chronic.

H—Appendicitis, subacute,

and so on, to the forty-first entitled "III defined or unclassified." Obviously, it would require an enormous expenditure of time and energy, to gather data on all the diseases included in these forty-one sections, by having recourse only to the individual patient charts ordinarily constituting the only source from which information may be had.

50 It is an object of the invention to provide a system, whereby to collect data for research purposes representing the experiences of many hospitals covering a wide territory, so that the findings will represent a fair average.

55 Referring to the drawings, 1 and 2 designate leader guides bearing the title of the section and appropriate data, as "Section 24, Intestines" as shown. Following the leader

60 guide, is the section mortality guide 3, upon which it is intended to record the total number of deaths caused by diseases of the intestines. Following the mortality guide are the disease guides, of which two numbered 4 and 5 are shown, and which may be

termed sub-guides. The disease guides carry the names of the diseases common to the intestines, such as "appendicitis" the title of guide 4 and "Intestinal obstruction" on guide 5. Accompanying each disease guide, is a mortality guide 6, upon which it is intended to record the number of deaths caused by the disease. Following the mortality guide, are the individual patient cards 7, preferably identified by number as "Case No. 1" by which it will be known in the hospital. The cards 7, are intended to carry data relating to the patient usually kept in hospital records, the data consisting ordinarily of the name of the patient, place of residence, nationality, age, and supposed ailment. Following the case cards, are the supplementary guides 8 or 18, of which two kinds only are shown, one under the caption of "Appendicitis" and the other under "Peritonitis," the latter being designated by the number 18. The supplementary cards contain in part such data from the cards 7 as is considered essential, the cards 8 being filed subsequently from time to time containing new important data which has subsequently developed, the cards 8 thus forming a cross index.

Sometimes the cards 7 disclose that a number of patients reside in the same locality, which, in research work, is significant in that causes of diseases may be traced to either insanitary conditions or contagion. This would be considered sufficiently important data to be recorded on the supplementary cards.

Thus, all diseases common to the intestines may be recorded, each of such diseases being separately recorded in one division, as for example the diseases "Appendicitis and intestinal obstruction" are here recorded in the two divisions represented by the guides 4—5—6—7— and 8. All of the mortality cards have preferably a black border or edge 19, which will show when the cards are stacked on edge, as in a drawer, whereby the divisions throughout the section are plainly discernible.

Further, all the cards (excepting the supplementary cards of each division corresponding to the cards 8 or 18), constituting divisions and headed by sub-guides and designating diseases common to the intestines, are preferably bodily of a definite color such as "buff," said color to serve as a symbol throughout all sections of the system whereby one familiar with same will know that all buff cards have reference to main diseases.

Following the buff division, is the sub-guide card 10, bearing the title "Injury to," which stands for "injury to the intestines" after which follows the mortality card 11, and the case card 12. To render the "Injury to" division plainly discernible these guides

are preferably green. Following this division is the division headed by the sub-guide 13 entitled "Secondary existing condition," having its death card 14, colored canary but 5 having no cases recorded. The following division covers "Complication" and has sub-guide 15 and a death guide 16 followed by the disease card 17, entitled "Peritonitis" and by the supplementary white card 18 entitled "Complication." This supplementary card 18 is filed in this division to indicate that one of the appendicitis cases subsequently developed peritonitis, it being noted that the corresponding card 8 (which has 15 buff diagonal lines on a white ground) in the buff section is blank, thus indicating that no important developments worth recording as special data have taken place in cases No. 1 and No. 2 filed in that section. Thus it is 20 a simple proceeding to readily ascertain how many cases acted as complication, and what other diseases the complication involved, and what other diseases were developed as the main disease progressed.

25 Incidentally, it is intended to record observations of unusual behavior on the supplementary cards such as 8 or 18, so that if the supplementary cards of the "Intestines" section, for instance, of my improved system, were collected from many hospitals, 30 they could be conveniently compared and studied by the student and finally returned to the respective institutions.

In order that the supplementary cards 35 may be readily returned to their proper division, each card bears, preferably, an identification mark, such as diagonal stripes 19, of the color of the division to which the card belongs. It is, also, to be impressed 40 with the date and year, so that data, may be compared as to periods of time by the student.

Following "Complication" come the three divisions "Chief operation", "Secondary operation", and "Operation for complication" 45 numbered 20—21—and 22, and colored red, purple and pink respectively. A mortality card 23, intended for the three divisions is provided. While no supplementary card is 50 shown in either of these divisions, it is to be understood, that such cards are intended to be used in all divisions as occasion may require. Thus, operations may disclose major adhesions, gall stones, tumors and the 55 like, all of which may be briefly recorded on supplementary cards in a manner to identify each operation, with the proper case number recorded in the buff division. An autopsy card 24 is the last card in the section 60 and is intended to receive such notes concerning findings as are thought sufficiently important to record.

In Figure 3 of the drawings, the several 65 divisions are suitably cross-hatched, to show, in a manner, how the colors offset each other,

so that one familiar with the system may go directly to the division containing the information sought. The stripes of the supplementary cards are also indicated on the edges thereof to facilitate finding them 70 when in search of supplementary information.

In Figure 4 is shown a supplementary card containing information, and Figure 5 illustrates a section of the classified index 75 file, showing "Sec. 21, Tongue" and six sub-guides cards giving preliminary information as to what are the subjects of record. in the filing system.

In the classification file, which may be a 80 separate drawer if desired, the leader card 25 is preferably yellow in color as indicated, and all the sub-guides 27 and 31 inclusive, are lavender, so that the section title may be readily found. The sub-guide 26 entitled 85 "Injury to" is green, which color prevails under this title throughout the system.

Each card has preferably a suitable perforation 32, having a slit 33 effecting a break in the lower edge of the card, so that 90 it may be inserted into an ordinary filing drawer.

To find information concerning a certain disease, as for example, appendicitis, the title under which this disease is classified is 95 first sought out and found to be "Section 24, Intestines". Reference to said section is then had, and the appendicitis cases there found filed.

I claim:

1. A record keeping system for use in hospitals, said system being coordinated to a classified group of titles relating to diseases common to certain parts of the body, said system comprising a plurality of sections of record-holding cards, each section including record-bearing cards 7, and record-bearing cross index cards, said cross index cards being divided into groups, said groups being located in accordance with the progressive steps of the disease designated by its title, and with associated conditions subsequently developing, and being rendered distinguishable from other cards by having identifying marks thereon, the record carried by said cross index cards differentiating from the record carried by the cards 7, in that it relates only to subject matter covered by one of said titles, whereby unusual behavior and phenomena developed by the diseases represented by said titles may be readily collected from the various sections of cards at one hospital and be compared with cross index cards of other hospitals, for the purpose set forth.

2. A record-keeping system for recording associated conditions of diseases and subsequent developments comprising a plurality of unitary packs of cards, each pack having a main guide card, the title thereon signi-

100

105

110

115

120

125

130

fying that the pack contains information relating to diseases which commonly attack only a certain part of the body, each pack being divided into groups, and each group having sub-guide cards, including a leader sub-guide bearing the title of the subject matter recorded in the group, and a mortality card bearing the record of deaths caused by conditions forming part of said subject matter.

3. A record-keeping system for recording the progressive stages of medical and surgical cases, and associated conditions and ultimate result, comprising a plurality of 15 unitary packs of cards, each pack having a main card bearing the title signifying that the pack contains records relating to diseases which commonly attack a certain part of the body, each pack being divided into 20 groups, and each group being adapted to receive data cards relating to a special condi-

tion, and having sub-guide cards including a mortality card for recording the deaths resulting from the condition recorded therein and a sub-guide card for recording the 25 sum of the deaths of all the groups.

4. A filing system for recording the progressive stages of a disease and filing supplementary matter, comprising sections of index cards, each section devoted to diseases 30 common to a particular part of the body, and being divided into divisions, each division being intended for recording information gleaned from a particular part of the regular course of a disease, and said division having guide cards with inscribed titles 35 designating the nature of said information including a death card in each division having a black border positioned so as to form the outer border of its respective division.

In testimony whereof I affix my signature.
JOSEPHINE M. LEAHY.
